UNITED STATES PATENT OFFICE.

FRANK J. HERRICK, OF NEW BRITAIN, CONNECTICUT, ASSIGNOR TO THE
NORTH & JUDD MANUFACTURING COMPANY, OF SAME PLACE.

DESIGN FOR A CLASP FOR BELTS.

SPECIFICATION forming part of Design No. 19,863, dated May 27, 1890.

Application filed April 24, 1890. Serial No. 349,400. Term of patent 7 years.

To all whom it may concern:

Be it known that I, FRANK J. HERRICK, a citizen of the United States, residing at New Britain, in the county of Hartford and State 5 of Connecticut, have invented and produced a new and original Design for Belt-Clasps, of which the following is a specification, reference being had to the accompanying drawings, forming a part thereof.

10 The figure is a front view of a belt-clasp showing my design.

The leading feature of my design consists in the outside frame *a*, having its surface ornamented with a series of geometrical or other 15 figures, and within this annular frame is a

star *b*, the points being in contact with the inner edges of the annular frame. This star is composed of a frame-work, so as to show through the interstices the background, that may be of any desired ornamental material. 20 On the opposite sides of this center piece are shown the oblong loops *c*, that form parts of the belt-clasp as a whole.

What I claim is—

The within-described design for a belt- 25 clasp, substantially as shown and described.

FRANK J. HERRICK.
